DESIGN FOR A LIGHTING FIXTURE

John H. Waterbury, Chicago, Ill., assignor to
Benjamin Electric Mfg. Company, Des Plaines,
Ill., a corporation of Illinois

Application July 23, 1937, Serial No. 70,589

Term of patent 7 years

To all whom it may concern:

Be it known that I, John H. Waterbury, a citizen of the United States, residing at Chicago, in the county of Cook and State of Illinois, have invented a new, original, and ornamental Design for a Lighting Fixture, of which the following is a specification, reference being had to the accompanying drawing forming a part thereof.

In the drawing,—

Figure 1 is a side elevational view of a lighting fixture embodying my new design; and
Fig. 2 is a perspective view thereof.

I claim:

The ornamental design for a lighting fixture substantially as shown.

JOHN H. WATERBURY.
